United States Patent Office

Des. 204,611
Patented May 3, 1966

204,611

KITE

Joseph L. Ventre, 113 N. Fir Ave., Inglewood, Calif.

Filed Aug. 26, 1965, Ser. No. 86,733

Term of patent 14 years

(Cl. D34—15)

FIGURE 1 is a perspective view taken from the lower right rear showing the design of my kite;

FIGURE 2 is a bottom plan view thereof;

FIGURE 3 is a side elevational view in cross-section thereof taken about the lines 3—3 of FIGURE 1;

FIGURE 4 is a front elevational view thereof; and

FIGURE 5 is a cross-sectional view thereof taken about the lines 5—5 of FIGURE 2.

I claim:

The ornamental design for a kite, substantially as shown.
